UNITED STATES PATENT OFFICE.

REGINALD AUBRY FESSENDEN, OF BROOKLINE, MASSACHUSETTS, AND LOUIS COHEN, OF WASHINGTON, DISTRICT OF COLUMBIA, ASSIGNEES, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

METHOD AND APPARATUS FOR AMPLIFYING ELECTRIC IMPULSES.

1,196,938.

Specification of Letters Patent. Patented Sept. 5, 1916;

Application filed September 2, 1913. Serial No. 787,630.

To all whom it may concern:

Be it known that we, REGINALD A. FESSENDEN and LOUIS COHEN, citizens of the United States, residing, respectively, at 5 Brookline, in the State of Massachusetts, and Washington, in the District of Columbia, have discovered or invented a certain new and useful Method and Apparatus for Amplifying Electric Impulses, of which the 10 following is a specification.

Our invention relates generally to the transmission of electric impulses and especially to feeble impulses such as used in wireless telegraphy and telephony; its primary object being to magnify or amplify 15 the received signals.

We have illustrated the invention in the accompanying drawing in which—

Figure 1 is a diagram illustrating circuits for explanation of the phenomena we have discovered; Fig. 2 is a diagram showing the arrangement for use of our discovery in amplifying signals received by electromagnetic waves. Figs. 3, 4 and 5, are 20 similar diagrams showing different arrangements of apparatus for wireless signals as will be hereinafter explained.

It is already known that if an alternating current circuit comprises two parts 30 which are closely contiguous parallel conductors, each one of which has an appreciable inductance, and a low resistance, then the current in each one of the said parallel branches may be larger than the current in the main circuit. In fact, if the resistances of the two parallel conductors be small as compared with $(L_1 - M)p$ and $(L_2 - M)p$, $(L_1$ and L_2 being the inductances of the parallel conductors, M the mutual inductance 35 and p the frequency multiplied by 2π —then the currents in the two parallel conductors will be opposite in phase, and the current in the main circuit equal to the difference between the currents in the two parallel conductors. (See *Formulae and Tables for the Calculation of Alternating Current Problems* by Louis Cohen pp. 143 to 144, and *Recent Researches of Electricity and Magnetism* by J. J. Thomson (1893 edition), pages 512 to 515.) We have investigated a somewhat analogous phenomenon,

that is, the effect of a small voltage introduced in one of the parallel conductors, and being superposed on a large voltage operating in the main circuit; or vice versa, a small voltage being introduced in the main circuit and superposed on a large voltage acting in one of the branches of the parallel conductors. This is illustrated in Fig. 1 where 7 represents a high frequency alternator of extremely small voltage, 8 another high frequency alternator of considerable voltage, and 9, 10, in circuit are two parallel conductors of considerable inductance and very closely coupled so there is no magnetic leakage. Each branch circuit also includes an adjustable inductance 11, and capacity 12, for tuning purposes. Now in the case of a simple circuit, if we had one electromotive force acting, and introduced an additional electromotive force, the per cent. change in current produced would be equal to the per cent. change in voltage produced by the additional electromotive force. For example, if there were a given electromotive force already acting, in a simple circuit, and then we introduced another electromotive force of say ten per cent. of the former one, the current in the circuit would merely be changed by ten per cent. But in the case of this arrangement shown in Fig. 1, we have found conditions entirely different; for the introduction of the additional small electromotive force due to source 7 will produce a much larger change in the current of the two branches than corresponds to actual per cent. change in voltage. The same phenomenon results from interchanging sources 7 and 8; but the constants of the coils 9, 10, will have to be different, and must be determined mathematically for every separate arrangement. In practice of wireless telegraphy, if the small current to be amplified is the effect of the voltage of incoming electromagnetic waves of the signal, it is more convenient to have it operate on the main circuit corresponding to the alternator 7 shown in Fig. 1. These phenomena have been investigated mathematically and tested experimentally by us, and apparently they depend on the proper choice of the electrical constants of the two coils 9 and 10,

which must be determined with mathematical precision. We have found that with the proper coil, the change in current produced in branch 9 by the introduction of a small 5 voltage as 7 is about six times the change produced by the same voltage acting in a simple circuit. If the indicating instrument is of such a form as to operate by this change in current, it is manifest that with 10 this arrangement we can detect a current only one-sixth the intensity necessary in order to operate the instrument in a simple circuit. And since the energy is proportional to the square of the current, it is also 15 clear that with this scheme we may detect signals of only one thirty-sixth the energy necessary to give a signal in a simple circuit.

For receiving, we may replace the source 20 7, in Fig. 1 by an antenna and thus utilize this arrangement for the amplification of the incoming signals. Furthermore, for the detection of the signals we prefer to make use of beats,—that is, we regulate the frequencies of alternation of the local source and the received waves, so that the difference in the frequencies will correspond to the frequency of an audible signal, say 1000 per second, which can be heard in an electrostatic heterodyne or electromagnetic heterodyne telephone as described in various Fessenden's patents for example, 1,050,728, dated January 14, 1913. The arrangement is shown in Fig. 2, where 13 is the antenna, 25 14 a loading or tuning coil, 9 and 10 the two branches of the parallel circuits, 15 condensers, 16 a tuning coil, 17 a high frequency alternator, 18 an electrostatic telephone, and 30 19 a ground. The operation of this arrangement is similar to that of Fig. 1: The incoming wave acts on the antenna and impresses a voltage as did the generator 7 in Fig. 1, and this small added electromotive force will produce a large change in the already existing current in receiver 18 due to 35 alternator 17. Also, since the two currents are of different frequencies, loud beats will be produced, the note being determined by the difference between the frequencies of the 40 two sources of electromotive force.

The coils 9, 10, are made up in any suitable manner so as to keep the high frequency resistance low, and are wound together on the same core and interlinked 45 with each other so as to make the coupling very close and the mutual inductance high. We have in one case arranged the number of turns on the two coils so that coil 10 is about thirty times the inductance of coil 9, 50 and found mathematically and experimentally that for the other constants used in this particular instance this ratio gives about the best results; but of course other ratios of inductance will also give an amplification, though not to the same extent. 55

Moreover, the inductances of the two coils must always be adjusted with relation to the other constants, with a view to always keeping the mutual inductance high. This requires adjustment of each coil whenever the other is changed. The exact relation between the inductances of the two coils depends upon their resistances, the coupling that can be obtained and the frequency.

Although the arrangement shown in Fig. 2 is preferred by us, various modifications may be used and obtain satisfactory results. In Fig. 3, for instance, the high frequency alternator 20, instead of being placed directly in one of the branch circuits, is connected through a transformer 21, 22. In Fig. 4, the alternator 20 and the receiver 18 are both coupled to the respective branches of the parallel circuits through transformers 21, 22, and 24, 25, respectively. Another arrangement is shown in Fig. 5 in which we utilize the electromagnetic attraction between the two coils 26 and 27 for the detection of the signals in place of the electrostatic attraction shown in the other figures, 90 various other modifications may be obviously made, the essential method of amplifying being always in the employment of a main local current on which the received current is superposed in one of the branches. 95

While we have illustrated the use of our discovery in wireless telegraphy, it will be understood that its use may extend to many other forms of apparatus.

Having thus described our invention and 100 illustrated its use, what we claim as new is the following:

1. Apparatus for amplifying feeble alternating currents, comprising a main circuit traversed by said current and having 105 branches including closely coupled conductors, means maintaining another alternating current in one of the branches of said circuit, and an indicator in the other branch operated by the combined effects of said currents, said conductors being connected to be opposed magnetically with respect to the additional current.

2. An amplifier for wireless signals, comprising a receiver circuit having an indicator therein, a shunt circuit having part of its conductor closely coupled with the receiver circuit, the coupled portions of said circuits having high mutual inductance and low resistance, and means maintaining an 115 additional alternating current in said circuits.

3. The method of amplifying signals in wireless telegraphy by passing the received oscillations through a plural branched conductor, said branches having parallel closely coupled portions of high mutual inductance and low resistance, and thereby inducing oscillations in said branches, and maintaining in said branches another alternating 125 130

current of near to but not the same frequency, and operating an indicator by the combined effects of the two currents.

4. The method of amplifying signals in wireless telegraphy, consisting in maintaining in the two branches of a circuit an alternating current, said branches having parallel closely coupled portions of high mutual inductance and low resistance, superposing on said current the received oscillations, and operating an indicator by the combined effects of the two currents.

In testimony whereof we have hereunto signed our names in the presence of the two subscribed witnesses.
